BUSHED TRANSFORMER TERMINAL

Edwin M. Meyer, Parkersburg, W. Va., assignor to
 Porcelain Products, Inc., Findlay, Ohio, a corporation of Delaware

Application November 3, 1939, Serial No. 302,767

3 Claims. (Cl. 174—153)

This invention relates to improvements in the insulated terminals of transformers, capacitors and similar equipment wherein high tension current is transmitted between a closed container or tank and the transmission line, a supply circuit or a distributing circuit. The principal problem is to provide for a conducting path for the current through an opening in a metallic container properly sealed against moisture, gases or dust particles. Equipment of this type requires an adequate sealing between the insulating member and the supporting receptacle or tank. Since such insulating members are usually made of rigid porcelain, the severe stresses created by the pressure of tightening the sealing members often results in damage to the porcelain, distortion of the cover plates and frequently an imperfect seal. It is an object of my invention to avoid abnormal stress concentration by eliminating sharp angles of the porcelain but placing the latter in pure tension free from bending thus increasing the ultimate strength of the porcelain.

A further object of my invention is to provide improved means for clamping the porcelain. Thus I use a clamp of ductile or deformable metal which will under the pressure applied, conform more closely to the adjacent surface of the bushing, increase the area through which pressure is applied and distribute this pressure more evenly.

A further object of my invention is to increase the extent of the sealing contact between the bushing and the plate upon which it is mounted.

Another object of my invention is to assemble a bushing with a seal in contact with the tank or other receptacle on the one hand and provide a second seal where the conductor is passed through the bushing so that the conductor may be connected and disconnected without disturbing the sealed condition of the bushing.

The following description will suggest other objects incidentally obtained by this invention.

As illustrative of the invention I have shown in the accompanying drawing the preferred embodiment of the invention. In the drawing,

Fig. 1 is a side elevation of the bushed terminal, some portions being indicated in vertical section;

Fig. 2 is a cross-section on the line 2—2 of Fig. 1 in the direction indicated by the arrows and

Fig. 3 is a perspective view of a segmental collar.

Generally speaking the terminal consists of a

bushing 6 mounted upon the cover plate 7 of a tank or other receptacle and in turn carrying the hooded cap nut 8 by which the conductor in the tank is connected to the outer line cable.

5 The bushing 6 is a hollow tubular piece of glazed porcelain of satisfactory insulating characteristics. The upper portion of the bushing has a series of porcelain ribs or petticoats 8. The lowermost petticoat 9 forms a shoulder 10 running completely around the bushing. This shoulder 10 is separated from the main body of the bushing by a circular groove 11. A ring of insulating material 12 fits below the shoulder 10 and forms a seal between it and the cover plate 7. The cover plate has an up-turned circular lip 13 of a diameter less than that of the shoulder 10 so that the lip comes opposite the groove 11. A gasket 14 held in the groove 11 rests upon the edge of the lip 13 and thus provides a second or additional sealing means at this point. The thickness of the gaskets 12 and 14 is such that they are simultaneously compressed with substantially equal pressure thus equalizing the compression upon the shoulder 10 and groove 11 and also increasing the area of sealing contact.

15 The lower end of the bushing 6 is in the form of an extension 15 having an intermediate flaring portion 16. This flaring or tapering portion 20 forms an extended conical seat for the clamp.

25 In order to equalize the pressure of the clamping action and to distribute it uniformly around the porcelain bushing I use a segmental clamp 17. This clamp is formed of three identical 30 segments 18 shown more particularly in Fig. 3. The inner walls 19 of these segments form a continuous conical wall having a taper or flare corresponding to that of the wall 16 on the bushing. Each end of each section is cut away for 35 half of its depth as indicated on the drawing. The outer lug 20 is provided upon the end farthest from the axis while the inner lug 21 is borne from the portion remaining nearer the axis. The lug 20 is tapped with a plain hole 22. The inner lug 21 has a screw-threaded opening 40 23. The diameter of the opening 22 is slightly in excess of the diameter of the opening 23.

45 Adjustment screws 24 pass through the plain hole 22 of one lug 20 and are threaded through the hole 23 in the adjacent lug 21. Beyond the lug 21 the bolt 24 is brought up against the lower face of the plate 7 and opposite the shoulder 10 and sealing gasket 12.

50 Each bolt 24 has a lock nut 25 bearing against the lug 20. The bolts 24 are advanced uniformly

to bring the clamping collar tightly against the sloping wall 16. The segments 18 of the collar are made of soft or deformable metal such that any inequality of contact will be compensated for by slight change in form of the metal thus providing a substantially uniform area of contact and pressure against the sloping wall 16. While I have shown three bolts 24 as pressing against the plate 7, this number may be increased where found desirable. However, the provision of two sealing gaskets 12 and 14 will provide adequate seal without multiplying the number of pressure points against the plate 7.

The bushing 6 has an axial passageway 26 running from end to end. This passageway is intended to receive a cable terminal at its upper end. A cap-nut 36 is provided with a lower portion flared outward to form a cap 38 of sufficient size to extend beyond the end of the bushing 6. The cap-nut is made of suitable cast metal and formed on one side of its central axis with an enlargement. This enlargement has a vertical opening 42 parallel to the longitudinal axis of the cap-nut. Set screws 43 threaded in the side of the enlargement serve to clamp the end of the cable or other conductor 44 within the opening 42.

The above described device needs little explanation as to its assembly or use. The bushing 6 is mounted upon the plate 7 with the gaskets 12 and 14 forming continuous seals between the lower petticoat 9 and the plate 7. The segments 18 of the clamp 17 are placed around the smaller diameter of the sloping wall 16 and the bolts 24 pass successively through the lugs 20 and 21 and the ends of the bolts brought against the plate 7 opposite the shoulder 10. Tightening these bolts brings an evenly distributed compression against an extended area of sloping walls 16 providing for a tight seal without unduly straining the porcelain.

By the provision of the device as just described an extremely efficient bushed terminal is provided for a closed receptacle. The bushing is well sealed around the aperture in the tank. At the same time the pressure is applied evenly

at the sealing edges by means of a clamp which is best suited for compression in the porcelain bushing itself. The compression surface is in the form of a cone of considerable area which receives the pressure uniformly throughout. The porcelain is put under simple tension and thus best adapted for satisfactory use.

While the novelty of the arrangement is apparent in the device when taken as a whole, still the several parts are individually novel as well. While I have shown a typical and the preferred form of the invention it is to be understood that the form, proportions and minor details may be varied widely without departing from the scope of the invention as stated in the appended claims.

What I claim is:

1. In combination with a cover plate having an opening with an upturned lip, a bushing having a peripheral shoulder with a groove opposite the lip on the plate, sealing means between said shoulder and plate and separate sealing means between said groove and lip, a conically flaring extension on the bushing, a segmental collar having a conical inner wall in extended contact with the extension and means carried by said collar for pressing against the plate on the side opposite the sealing means.

2. In a device of the class described, a multiple segment collar with a circular inner wall having a conical tapering slope, said segments having interfitting end sections, one end section of each segment being screw-threaded, the other end section being bored and adjusting screws passed through the end sections of adjacent segments.

3. In a device of the class described, a multiple segment collar with a circular inner wall having a conical tapering slope, said segments having overlapping end sections, one end section of each segment being screw-threaded, the other end section being bored, and adjusting screws passed transversely through the end sections of adjacent segments.

EDWIN M. MEYER.
